ELLIPSOGRAPH

Filed Sept. 17, 1928

UNITED STATES PATENT OFFICE

ALFONS DIETRICH, OF GLENDALE, LONG ISLAND, NEW YORK

ELLIPOGRAPH

Application filed September 17, 1928. Serial No. 306,294.

The main object of this invention is to provide a device for scribing ellipsoid or any other irregular or symmetrically shaped outlines.

5 Another object of this invention is to provide a compass suitable for scribing any shape or form of outline, irrespective of its symmetry or irregularity, with the aid of a replaceable master disc which forms part of

10 the device.

Still another object of this invention is to provide a compass which is capable of scribing symmetrical or irregular outlines of any dimension within the limits of the instrument.

15 The above and other objects will become apparent in the description below, in which characters of reference refer to like-named parts in the drawings.

20 Referring briefly to the drawings, Figure 1 is a partly sectioned side elevational view of the compass.

Figure 2 is a top plan view of the same.

25 Figure 3 is an end elevational view of Figure 1.

Figure 4 is a fragmentary perspective view of the scribing beam.

Figure 5 is a perspective view of the adjustable rail.

30 Referring in detail to the drawings, the numeral 10 indicates a stud which forms part of the base of the device. This stud has projecting downwardly therefrom a trio of prongs 11, 12 and 13. The prongs are linearly aligned and are adapted to pierce the paper or material upon which the outline is to be drawn. A trio of prongs are used to place the instrument upon an axis of the figure to be drawn and also to center the compass upon the figure being drawn. The stud

35 10 has a stem 14 provided thereon which inserts into a canal 15 formed in the lower end of the compass spindle 16. This stem 14 is secured in place in the canal 15 by a thumb screw 17. The upper end of the spindle has a face plate 18 formed thereon on which is seated a replaceable and special master disc 19. This master disc is provided with a periphery or outline identical with the outline which is to be drawn by the compass. Sur-

mounting the master disc and secured thereto is an auxiliary spindle 20 provided with a flange 21 at one end which secures directly to the master disc and the face plate 18. At the upper end of the auxiliary spindle a reduced extension 22 is provided. This reduced extension has an opening therein into which is inserted the shank 23 of a rotatable stud 24. The stud rests upon the upper end of the extension 22, which latter is non-rotatable, and is retained in axial relation with the auxiliary spindle 20 by a collar 25 in which is contained the stud 24 and the extension 22. The extremities of the stud 24 and the extension 22 are provided with encircling flanges which form shoulders in the collar 25. This collar 25 retains the stud in position adjacent the auxiliary spindle. The stud 24 has a hinge head 26 formed thereon. This hinge head is slotted and has a downwardly extending pointed projection 27 to which is pivotally attached the tongue 28 located at the upper end of a sleeve 29. A finger stud 30 surmounts the head and has for its purpose to enable the user of the device to grip the compass in convenient fashion. The sleeve 29 is hollow throughout the greater portion of its length and is provided with a longitudinal slot 31 extending from one end to a position near the tongue 28. Said sleeve member 29 has a slide block 32 adjustably mounted therein. This slide block is provided with a channel 33 into which one end of a follower fork 34 is pivoted. This forming fork has its opposite ends flared in opposite directions to provide a depression or saddle in which the edge of the master disc 19 registers. The slide block 32 is normally urged toward the outer open end of the sleeve 29 by a coil spring 35 which is confined within the sleeve. Below the slide block, and slideable within the sleeve, is a circular shank 36 which has a bifurcated end 37. The bifurcated end 37 of the shank engages and is secured to one or the other of the tongues 38 or 39 of an I-shaped rail 40. These ears are located on the upper flange 41 of the I-shaped rail and the shank 36 is adapted to be replaced by another shank of longer or shorter length according to the size of the master

discs which are to be used. The rail consists of an upper flange 41, as stated, and a lower flange 42 parallel to the upper flange. These flanges have their adjacent surfaces dove-tailed, as indicated by the numeral 43, and are connected by a web 44. The web is provided with a slot 45 which extends throughout the greater portion of its length.

The rail 40 is supported on a compass beam 10 which comprises a pair of parallel extending arms 46 and 47. The sides of these arms are dove-tailed and register in the dove-tailed portions of the rail on both sides of the web. The arms 46 and 47 of the compass beam are 15 separated from each other by a channel 48 which channel is open at one end and is closed at the other end. The closed end 49 of the compass beam, where the parallel arms 46 and 47 are joined, is provided with an opening 50 in which a reduced neck 51, formed on the lower end of the spindle 16, is received. This compass beam is supported upon the face of the stud 10 and, in turn, supports the rail 40. A pin 52 is anchored in the separated 25 ends of the parallel arms 46 and 47 of the compass beam and passes through the slot 45 in the rail, said pin serving as a limiting member to prevent the rail from being detached from the compass beam.

30 A ridge 53 projects from the lower flange 42 of the rail. This ridge serves as a guide for the head 54 of a drafting pen 55. The head of the drafting pen is secured to the ridge in any of a number of adjustable positions by a thumb screw 56.

35 The side of one or the other of the arms 46 or 47 of the compass beam may be provided with linear graduations 57 which determine the scale to which the outline of the figure is to be drawn. To retain the forming fork continually in engagement with the edge of the master disc a spring 58 is secured to the lower end of the spindle 16 and the bifurcated end 37 of the shank 36.

40 The device is particularly adapted to be used in preparing outlines other than circles, but circles can also be drawn with the instrument. Such irregular outlines as alphabet letters, in script or printed form, or ellipses, ovals, or cam curves, may all be constructed with this device, to any scale required, within the limits of the instrument.

45 In using this device the major and minor axes of an irregular outline are first laid out. The prongs, which are linearly aligned, are then positioned upon one or the other of the laid-out lines, with the parallel prong 12 piercing the intersection of these guide lines. The master disc desired has, previous to this operation, been mounted in place between the spindle 16 and auxiliary spindle 20 through the medium of the screws 59, and the edge of the master disc has been inserted into the saddle of the forming fork 34. The 55 upper head 26 of the stud 24 is rotatable about

the axis of the auxiliary spindle and, as the head 26 carries suspended therefrom the sleeve 29 in which the slide block 32 is located, the entire structure suspended from the head 26 is rotatable therewith. At the lower end 70 of the spindle 16 the compass beam is rotatably mounted by inserting the reduced portion 51 of the spindle 16 into the opening 50 of the compass beam. This compass beam has mounted slidably thereon the rail which 75 serves the double purpose of an anchoring member for the pen 55 and, by reason of the dove-tailed surfaces on the flanges 41 and 42, locks the arms 46 and 47 in place in such manner that these arms will not be damaged, bent 80 or deformed while the device is in use. The spring 58 constantly retains the forming fork 34 in sliding contact upon the outline of the master disc and thereby insures accuracy of duplication of the outline to the scale desired.

85 It is to be noted that certain changes in form and construction may be made without departing from the spirit and scope of the invention.

50 I claim:

1. A compass for scribing outlines of predetermined contour comprising a vertically positioned spindle, means for retaining said spindle in stationary position, a disc having the desired outline mounted rigid with said spindle, a head mounted rotatably on said spindle, a compass beam extending from said spindle and rotatable thereabout, said compass beam extending at right-angles to said spindle and comprising spaced-apart parallel arms thereon, said arms having their side edges beveled converging outwardly, an I-shaped rail slidable on said compass beam between the arm thereof, said rail being beveled to fit said parallel arms to prevent spreading of the latter, and means connected to said rail and rotatable head engaging said disc, said disc being adapted to change the position of said rail with respect to said arms as said beam rail and head are rotated about the spindle.

100 2. A compass for scribing irregular or symmetrical outlines comprising a vertically positioned spindle, means for retaining said spindle in stationary position, a disc having the desired outline mounted rigid with said spindle, a head mounted rotatably on said spindle, a compass beam extending from said spindle and rotatable thereabout, said compass beam extending at right-angles to said spindle and having spaced-apart parallel arms thereon, said arms having their sides dovetailed, an I-shaped rail slidable on and between the arms of said compass beam, said rail being dovetailed to receive said parallel arms to prevent spreading of the latter, said disc being adapted to move said rail, a sleeve depending from said head, a slidable follower block in said sleeve, means slidable in said 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 5 sleeve connected to said rail for sliding the latter along said compass beam, and means mounted pivotally on said follower block engaging said disc for radially shifting said sleeve.

10 3. A compass for scribing irregular or symmetrical outlines comprising a vertically positioned spindle, means for retaining said spindle in stationary position, a disc having the desired outline mounted rigid with said spindle, a head mounted rotatably on said spindle, a compass beam extending from said spindle and rotatable thereabout, said compass beam extending at right-angles to said spindle and having spaced-apart parallel arms thereon, said arms having their sides dovetailed, an I-shaped rail slidable on and between the arms of said compass beam, said rail being dovetailed to receive said parallel 15 arms to prevent spreading of the latter, said disc moving said rail reciprocally, a sleeve depending from said head, spaced-apart tongues on said rail, a shank movable in said sleeve, said shank being pivotally connected to one of said tongues, a slide block in said sleeve, means pivotally mounted in said slide block engaging said disc for radially shifting said sleeve and rail, as said rail and associated parts are rotated about the spindle, 20 and means for retaining said second-named means in engagement with said disc.

25 4. A compass for scribing irregular or symmetrical outlines comprising a vertically positioned spindle, means for retaining said spindle in stationary position, a disc having the desired outline mounted rigid with said spindle, a head mounted rotatably on said spindle, a compass beam extending from said spindle and rotatable thereabout, said compass beam extending at right-angles to said spindle and having spaced-apart parallel arms thereon, said arms having their sides dovetailed, an I-shaped rail slidable on and between the arms of said compass beam, said 30 rail being dovetailed to receive said parallel arms to prevent spreading of the latter, a sleeve depending from said head, spaced-apart tongues on said rail, a shank movable in said sleeve, said shank being pivotally connected to one of said tongues, a slide block in said sleeve, a forming fork pivotally mounted in said block, said sleeve having a longitudinal slot therein, and said forming fork passing through said slot and being 35 adapted to ride on the periphery of said disc, and a spring connected to said spindle and said shank for retaining said forming fork in engagement with the periphery of said disc.

40 5. A compass for scribing outlines of predetermined contour comprising a vertical spindle, means for retaining said spindle in stationary position, a disc having a desired outline rigidly mounted on said spindle, a 45 rotatable head surmounting said spindle, a

compass beam extending rotatably from said spindle at right-angles thereto, a rail slidable on said compass beam, extensible means pivotally suspended from said rotatable head riding upon the marginal edge of said disc, 50 said extensible means being connected to said rail, and means on said rail for scribing an outline smaller in area than the area of said disc.

55 6. A compass for scribing outlines of predetermined contour comprising a vertical spindle, means for retaining said spindle in stationary position, a disc having a desired outline rigidly mounted on said spindle, a 60 rotatable head surmounting said spindle, a compass beam extending rotatably from said spindle at right-angles thereto, a rail slidable on said compass beam, extensible means pivotally suspended from said rotatable head riding upon the marginal edge of said disc, 65 said linearly spaced-apart ears projecting from said rail, said extensible member being connected to one of said ears according to the size of said disc, one end of said rail being extending under said disc, a bow pen 70 mounted on said rail for adjustment therealong, said bow pen being adapted to be adjusted to a position beneath said disc for bounding an area of the same shape as said disc but of smaller area.

75 7. A compass for scribing outlines of predetermined contour comprising a vertically positioned spindle, means for retaining said spindle in stationary position, a disc having the desired outline mounted rigid with said spindle, a head rotatably mounted on said spindle adapted to be gripped by the fingers when in use, a compass beam extending from said spindle and rotatable thereabout, an arm suspended from said head and movable therewith and bearing against said disc, an I-beam 80 pivotally connected to said arm and slidable on said compass beam, said compass beam extending at right-angles to said spindle and comprising spaced-apart parallel arms thereon, said disc being adapted to guide the rail in extensible movement on said arms.

85 In testimony whereof I affix my signature.
ALFONS DIETRICH.
